UNITED STATES PATENT OFFICE.

SAMUEL OTHO HOLLAND, OF SALISBURY, NORTH CAROLINA, ASSIGNOR OF ONE-HALF
TO BASCUM L. UMBERGER, OF CONCORD, NORTH CAROLINA.

COLLAPSIBLE-RIM TOOL.

Application filed October 11, 1921. Serial No. 507,013.

To all whom it may concern:

Be it known that I, SAMUEL OTHO HOLLAND, a citizen of the United States, and resident of Salisbury, in the county of Rowan and State of North Carolina, have invented certain new and useful Improvements in Collapsible-Rim Tools, of which the following is a full, clear, and exact description thereof.

10 My invention relates to a tool for expanding collapsible or other demountable rims, and one of the objects thereof is to provide a tool of this character which is of the most simple construction possible, and which is 15 inexpensive to manufacture.

Another object of my invention resides in the provision of a tool of this character which forms no part of the rim and is entirely independent thereof.

20 Another advantage of my invention is that it may be applied to the rim instantly and without the necessity of making any adjustments.

Still another object of my invention is 25 to provide a tool of this character which is foldable in such manner that it occupies a minimum space.

Other objects and advantages of my invention will appear as the description proceeds.

I will now proceed to describe one particular form of my invention, it being understood that those skilled in the art may make many changes and modifications therein 35 without departing from the spirit of my invention as defined in the appended claims; and the drawings forming part of this application are therefore to be considered merely as illustrative and not in any limiting sense.

In the drawings:

Figure 1 is a perspective view of a rim with the tool applied thereto.

45 Figure 2 is a side view of the tool and rim, the latter being in section, and showing the position of the parts when the rim is expanded.

Figure 3 is a plan view of the tool applied to the rim, and

50 Figure 4 is a perspective view of the tool in its folded position.

Referring to the drawings more in detail, numeral 1 indicates a rim, which in the present instance is of the collapsible 55 type, though it will be understood that my

invention is equally well adapted to use with any other type of demountable rim.

The tool comprises the two links 2 and 3, hingedly connected as indicated by numeral 4; and a latching device 5 hingedly connected to the link 3 as indicated by numeral 6.

Suitable lugs 7 and 8 are provided on the rim, and are located adjacent the ends thereof. The link 2 is provided with a notch 9 for engaging one of the lugs, and the link 3 has the latch member 5 connected therewith, and this latch member is shown as provided with a key-hole slot 10 for engaging the other lug.

70 The operation of the tool will now be described.

It is well known that after a collapsible or other rim has been placed on a tire, it is necessary to apply a very strong force in order to expand the rim to its normal position and thus permit the ends of the rim to snap into position. The necessary force is obtained in the use of my invention by the toggle action of the links 2 and 3, as will clearly appear hereinafter.

Assuming the rim to be in the position shown in Figure 1 then it is only necessary to place the notch 9 and keyhole slot 10 in engagement with the lugs provided on the rim, and when this has been done, the links 2 and 3 form a toggle, as clearly shown in Figure 1. It will be apparent that it is only necessary to step on the toggle, thereby causing the ends of the links to expand the rim to its normal locking position.

Attention is here called to the fact that the hinge 4 between links 2 and 3 is on the under side of the toggle, so that as the rim expands and approaches its normal position, this hinge strikes the upper end of the rim and causes it to snap into position.

After the rim has been expanded the tool is removed from the rim and folded in the manner shown in Figure 4, so that a minimum space is occupied by the tool when it is not in use.

From the above description it will be clear that the collapsible rim tool which I have invented is of the most simple construction possible, and is also inexpensive in manufacture; that the tool forms no part of the rim itself, and is entirely independent therefrom, and that the tool is adapted to use in connection with any type

of demountable rim, it being only necessary to provide on the rim some means for engaging the ends of the links; that the tool may be applied to or removed from the rim 5 instantly, and without the necessity of making any adjustments; and that when not in use the tool may be folded on itself so that it occupies a minimum space.

Having fully described my invention, 10 what I claim as new and desire to secure by Letters Patent is:

1. A toggle device for expanding detachable split rims, comprising two flat plates each adapted at one end to engage and 15 thrust the rim, said plates being connected by a hinged joint affording a sufficient projection on one side of the device to force

the meeting ends of the rim out into line when the toggle is flattened.

2. A toggle device for expanding detachable split rims, including two flat plates foldable upon each other, and a third flat plate foldable upon one of the first-mentioned plates, said third plate having an aperture affording means for engaging a 25 portion of a rim.

3. A collapsible rim tool comprising three sections hingedly connected, two of the sections being links for forming a toggle, and the third section being a latching device, 30 said latching device being provided with a key-hole slot.

SAMUEL OTHO HOLLAND.
